JOHN McCAGEY, OF PROVIDENCE, RHODE ISLAND, ASSIGNOR TO THE NEW ENGLAND BUTT COMPANY.

GUIDE FOR MACHINES FOR COVERING WIRE.

SPECIFICATION forming part of Letters Patent No. 439,675, dated November 4, 1890.

Application filed May 7, 1890. Serial No. 350,884. (No model.)

To all whom it may concern:

Be it known that I, JOHN McCAGEY, of Providence, in the county of Providence and State of Rhode Island, have invented certain new and useful Improvements in Guides for Machines for Covering Wire; and I do hereby declare that the following is a full, clear, and exact description thereof, reference being had to the accompanying drawings, and to the letters of reference marked thereon, which form a part of this specification.

This invention relates to guides for winding-machines used for covering wire for electrical and other purposes, and is an improvement on the invention described in my application, Serial No. 347,950. It is illustrated in the accompanying drawings, of which—

Figure 1 shows an elevation of the winding part proper of the machine described in the application above referred to. Fig. 2 is a front elevation, on an enlarged scale, of the wire guide and supporter on the end of the flier. Fig. 3 is a top view of the guide shown in Fig. 2. Fig. 4 shows a horizontal section 25 of the guide, taken on line xx in Figs. 1 and 2.

The part of the winder shown in the drawings consists of a plate or carrier e , revolving around a stationary tube a , made fast in the frame below. The plate or carrier e carries the spool d , holding the covering material, the flier-arm j , and stud m . The wire z to be covered is drawn through the tube a from a reel placed in the machine below. The flier j is not made fast in the plate e , but left free 35 to be turned away from over the spool d when it is necessary to put on a full spool. The spring o on the flier has one end attached to the flier and the other rests against the pin m , so as to hold the arm over the spool while 40 in operation, the pin n on the flier constituting a stop, which contacts with pin m to arrest the flier after it has been turned to proper position by the spring.

This invention is an improvement on that 45 part of the machine described in the application before referred to which provides for guiding and supporting the wire while it is having the thread wound upon it, and is mainly confined to the construction of the 50 guide at the end of the flier where the thread is applied to the wire.

In covering very fine wire it has heretofore proved to be very difficult to hold the wire straight against the strain of the threads, where, as in central-spool winding, this strain 55 can only be applied on one side of the wire, and it is necessary to draw the thread very tightly around the wire to insure the threads spreading out evenly and not riding one on another, and where the covering is limited to 60 a very thin layer, as in wire for covering armatures for dynamos, &c., whereon a wire of No. 30 only .250 of an inch are allowed for the increase in the diameter in a covering of silk thread. The wire, being very fine, is not 65 strong enough to bear sufficient tension to hold it straight against the strain of the thread, and if the wire is allowed to sag or bend the tendency will be for the thread to wind in the hollow and not evenly on the wire. This difficulty I obviate by forming a vertical V -shaped trough on the end of the flier-arm directly over the opening in the hollow spindle, through which the wire is drawn, so that the wire while being wound will lie in the bottom 75 of this V -shaped guide, (see Fig. 3,) and a notch a' is cut in one side of the guide, not quite down to the bottom of the groove, but so as to leave enough of that side of the groove to about come up to the outer side of the 80 wire. (See Fig. 4.) This notch a' is to allow the thread v to come to the wire, and it will be readily seen that the wire z has a support all along its sides and back sufficient to prevent the thread v from drawing it out of a 85 straight line by any tension that the thread will bear without breaking.

The thread for the purpose of making as thin a covering as possible is made up of several strands too fine and weak to bear winding 90 separately, but which are spread out without twist side by side on the wire, and this spreading of the strands is accomplished by passing them over the edge of the side of the groove that is left in the notch a' , as before mentioned, and shown in Fig. 4. By this arrangement any size of wire, however fine, or a thread, can be successfully and rapidly covered with a close even covering, if desired, which is of great importance in view of the continued increase of the use of electricity in the arts. 100

The parts of the complete machine other

than the guide herein described are made as set forth in the description given in the application before referred to in this specification.

Having thus described my improvements,
5 what I claim as my invention is—

A revolving carrier, in combination with a guide for use in machines for covering wire, constructed to lead the covering material to the wire and having a wire-receiving groove
10 or trough, the sides whereof sustain the wire

against lateral flexure resulting from the strain of the covering material, and the said guide being imperforate at that point where the winding takes place, substantially as described.

JOHN McCACHEY.
